United States Patent Office

Des. 180,443

Patented June 11, 1957

180,443

ROOM THERMOSTAT

Henry Dreyfuss, South Pasadena, Calif., assignor to Minneapolis-Honeywell Regulator Company, Minneapolis, Minn., a corporation of Delaware

Application February 11, 1954, Serial No. 28,972

Term of patent 14 years

(Cl. D52—7)

FIG. 1

FIG. 2

FIG. 3

Figure 1 is a front elevation of a room thermostat embodying my new design;

Figure 2 is a side elevation of the device shown in Figure 1, and

Figure 3 is a front perspective view of the device shown in Figure 1.

The dominant features of the design reside in the portion shown in full lines.

I claim:

The ornamental design for a room thermostat, substantially as shown and described.
